UNITED STATES PATENT OFFICE.

HORACE M. HOOVER, OF PERRYSBURG, OHIO.

MACHINE FOR PRODUCING WOOD FIBER.

SPECIFICATION forming part of Letters Patent No. 624,938, dated May 16, 1899.

Application filed September 1, 1898. Serial No. 689,981. (No model.)

To all whom it may concern:

Be it known that I, HORACE M. HOOVER, of Perrysburg, county of Wood, and State of Ohio, have invented certain new and useful 5 Improvements in Machines for Producing Wood Fiber; and I do hereby declare that the following is a full, clear, and exact description of the invention, which will enable others skilled in the art to which it appertains to 10 make and use the same, reference being had to the accompanying drawings, and to the figures of reference marked thereon, which form part of this specification.

My invention relates to a machine for producing wood fiber, and has for its object to 15 provide a mechanism whereby there may be manufactured a fibrous product from a solid bolt of wood. The product is designed more particularly for use as a base for plaster for 20 plastering material, and therefore it is essential that the disintegrated wood shall be fibrous as contradistinguished from the product in grinding the bolt for wood-pulp as used in the manufacture of indurated fiber goods. 25 I have provided for producing the fiber from the wood longitudinally of the bolt or, in other words, coincident with the grain of the wood, whereby there is produced a fiber of the desired length, and have provided for a 30 feed of the bolt whereby the fiber may be of extreme fineness.

In the drawings, Figure 1 is a front elevation of a machine constructed according to my improvement. Fig. 2 is a rear elevation 35 of the same. Fig. 3 is a plan of the same. Fig. 4 is a section on the line $\alpha\alpha$, Fig. 3, looking in the direction of the arrow.

Referring now to the details of the drawings, 1 designates standards supporting the 40 bed 2, and which has secured upon its face and one end thereof, in diametrically opposite position, standards 3, in which is journaled an arbor 4, having mounted thereon a plurality of saws 5, spaced equidistant and in 45 oblique position to the mandrel. The obliquity is such as to present a revolving reciprocating cutting edge to a bolt of wood 6, fed thereto by the operation of the mechanism, and which cutting edge is thereby adapted to 50 reduce the bolt of wood 6 into a fibrous material by the reciprocating movement result-

ing from the obliquity of the saws upon the arbor 4 during the revolution thereof.

The bolt of wood 6 is fed to the saws and is supported upon one end by a spur 7, having formed thereon a tenon 8, adapted to enter a socket 9, which is formed in the inner end of the mandrel 10. The opposite end of the bolt is supported by a movable centering-pin 12. Both the mandrel and pin are supported and journaled in brackets 13, integral with a carriage 14, supported upon and held in ways 15, formed upon the face of the bed 2 in parallel alinement.

The bolt of wood is caused to revolve during its reduction to fiber, and I have therefore devised means for gradually increasing the velocity of the revolving bolt of wood 6 as its diameter is reduced by the cutting of the gang of saws. One end of the arbor 4 65 projects beyond the bed-plate and has secured thereon a driven pulley 16 and a driving-pulley 17, (see Fig. 2,) from which motion is transmitted by means of a belt 18 to a pulley 19, mounted upon an arbor 20, which 70 is journaled in brackets 21, secured to the side of the bed 2. From the arbor 20 motion is transmitted to an arbor 22 by means of an intermeshing miter-gear 23. The arbor 22 is 75 also held in the brackets 21 and is movably supported upon the opposite end in a movable bearing 24, mounted upon a shaft 25, which is journaled in the bed of the mechanism and has secured thereto a friction-disk 26, adapted to be engaged by a friction-pulley 27, movably mounted upon the arbor 22. 80 From the shaft 25 motion is transmitted by means of a train of gears 28, located upon the opposite end of shaft 25, from which motion 85 is transmitted to a bevel-gear 29, secured to or integral with a member 30 of the train of gears, and which member is journaled in a bracket 31, secured to the bed-plate 2. The bevel-gear 29 is adapted to intermesh with a coincident bevel-gear 32, which is secured to 90 a shaft 33. The shaft 33 is journaled in a bracket 34, secured to the bracket 31, and the opposite end is journaled in a bearing 35, secured to the standards 3. The central portion of the shaft 33 is supported in bearings 36 and 37, (see Fig. 1,) integral with the brackets 13, and between said brackets there is 95 100

mounted a worm 38 upon the shaft 33, and which worm engages a coincident gear 39, secured to the mandrel 10. A feather 33' is formed longitudinally upon the shaft 33, whereby revolution is transmitted by means of the worm-gear to the bolt of wood supported upon the slide.

The revolution of the mechanism as described in the foregoing will cause the bolt of wood 6 to revolve during its reduction, and in order to provide a continuous feed as the bolt 6 is reduced I have provided a train of gears 40, transmitting motion at a reduced velocity to an arbor 41, journaled in the carriage 14. The train of gears are set in motion by means of a pinion 42, secured upon the arbor 10. The other members of the train of gears are secured to an arm 43, mounted upon the mandrel 10 and the arbor 41. Upon the arbor 41 of the inner side of the bed-plate there are pinions 44, adapted to engage movable rack-bars 45, which are pivotally secured at the rear of the bed. The front end 46 is supported upon brackets 47, which are secured to an arbor 48, journaled in the sides of the bed. The brackets 47 are formed with steps 49 and are normally caused to hold the rack-bars 45 in operative position by means of springs 50, secured to an arm 51 of the bracket and to the front standard 1 and arranged to force said arm 51 upward. The brackets 47 may be moved by hand by means of handles 52, (see Fig. 3,) secured to the arbor 48, so as to bring the rack-bars 45 into engagement with the pinions 44 or disengagement to allow free and independent movement of the slide.

53 designates a lever pivotally secured upon the inner side of the bed 2 and is connected by means of a bar 54, pivoted to the movable bracket 47. Upon the under side of the carriage 14 there is secured a pin 55, adapted to engage the projecting end 56 of the lever as the slide is caused to traverse upon the ways 45 toward the gang of saws. The contact of the pin with the free end of the lever 56 will cause a disengagement of the rack-bars 45 with the propelling - pinions and will cause a consequent stoppage of the slide.

50 57 designates a rack-bar movably secured to the side of the bed by means of clamps 58 and has formed upon its front end a pendent eye 59, to which may be fastened a cable or chain 60, adapted to run over a pulley 61, 55 which is also pivotally secured to the bed-plate, and the chain has secured to its free end a weight portion 62, adapted to retract the rack - bar into its original position, as shown in Fig. 2. The lug 63 is integral with 60 the carriage 14 and pendent therefrom and is adapted to engage a shoulder 64, formed upon the rack-bar 57, whereby as said carriage travels toward the saws a simultaneous movement is transmitted to the rack - bar, 65 which is adapted to engage a segmental toothed arc 65, which is supported in an intermeshing position by means of a bracket

(shown in dotted lines) secured to the side of the bed 2. A rod 66 is pivotally secured at one end to the arc 65 and at its other end to 70 a ring 70, fitting in a groove in the friction-pulley 27, so that as the arc 65 is moved by the rack 57 the rod 66 pushes said friction-pulley inwardly toward the center of the friction-disk 26 as the carriage approaches the 75 saws during the reduction of the log or bolt of wood to fiber, whereby the surface speed of the bolt is equalized during the process of reduction, and thus a fiber of even texture is produced. 80

67 designates a locking-lever pivotally secured to the bracket 68 and connected to the movable bearing 24, mounted upon the shaft 25. The object of this movable bearing is to provide means whereby the revoluble movement of the bolt of wood 6 may be arrested at any position without stopping the revolution of the saws. 85

It will be seen from the foregoing that in the operation a bolt of wood being mounted 90 upon the carriage, the mechanism being set in motion, the bolt of wood is automatically fed to the gang of saws, and as the diameter of the bolt of wood is reduced by removing stock thereof in a fibrous state the velocity of 95 the revolution of the bolt of wood is proportionately increased as the diameter of the bolt is decreased by means of the inward travel of the friction-pulley in engagement with the driven disk mounted upon the shaft 25. 100

What I claim is—

1. The combination in a machine of the class described, of a series of rotating saws, a carriage traveling toward the saws, means for revolving a log held on said carriage, a 105 rack moved in one direction by said carriage, means for returning it, a pivoted toothed arc meshing with said rack, a rotating friction-pinion, a friction-disk operated by said pinion, a connection between the arc and the 110 friction-pinion, and intermediate gearing between the friction-disk and the means for revolving the log, substantially as described.

2. The combination in a machine of the class described, of a frame, a series of rotating circular saws mounted thereon, a carriage traveling on the frame, means on said carriage for holding a log, mechanism for revolving said log, a rack 57 supported by said frame, a lug 63 on the carriage for operating 120 said rack in one direction, a weight 62 for moving it in the other direction, a pivoted toothed arc 65 engaging with the rack, a rotary friction-pinion 27, a rod 66 connected with the arc and pinion, a friction-disk 26 operated by said pinion, and intermediate gearing 125 between said disk and the mechanism for revolving the log, substantially as described.

3. The combination in a machine of the class described, of a frame, a series of rotating circular saws mounted thereon, a carriage traveling on said frame, a rotating shaft 33 supported by the frame, a worm 38 sliding on and revolving with the said shaft, a man-

5 drel 10 mounted on the carriage, a worm-wheel 39 fast on said mandrel and coacting with the worm, a rack 45 attached to the frame, a pinion 44 mounted on the carriage and engaging with the rack and intermediate gearing between the mandrel 10 and said pinion 44, substantially as described.

10 4. In a machine of the character described, a frame, a series of rotating circular saws mounted thereon, a carriage traveling on said frame, a rotating shaft 33 supported by the frame, a worm 38 sliding on and revolving with said shaft, a mandrel 10 mounted on the carriage, a worm-wheel 39 fast on said mandrel and coacting with the worm, a rack 45 pivotally attached to the frame, a pinion 44 mounted on the carriage and engaging with the rack, intermediate gearing between the mandrel 10 and said pinion, a stepped bracket 15 47 on which the rack rests, and means for tripping said bracket as the carriage nears the end of its motion, substantially as described.

20 5. In a machine of the character described, a frame, a carriage, means on said carriage for giving a log a rotary motion, a pinion also mounted on the carriage, intermediate gear-

ing connecting the log-turning means with said pinion, a rack pivotally connected to the frame at one end, and a tripping device operated by the motion of the carriage, as it 30 nears the end of its travel, substantially as described.

6. In a machine of the character described, a frame, a carriage having means for giving a log a rotary motion, a pinion mounted on 35 the carriage, intermediate gearing connecting the pinion and log-turning devices, a rack pivotally connected to the frame at one end, a bracket supporting the free end of said rack, a lever pivoted on the frame, a rod connected 40 to the bracket at one end and to the lever at its other end, and a tripping-pin on the carriage for operating said lever, substantially as described.

In testimony that I claim the foregoing as 45 my own I do hereby affix my signature in presence of two witnesses.

HORACE M. HOOVER.
